United States Patent

Des. 237,793
Patented Nov. 25, 1975

237,793

WALL PANEL

J. L. Marcel Begin, Toronto, Ontario, Canada
(115 Sexton Crescent, Willowdale, Ontario, Canada)

Filed Mar. 21, 1973, Ser. No. 343,226

Term of patent 14 years

Int. Cl. D25—01

U.S. Cl. D13—1 J

Fig. 2

FIG. 1 is a front elevation view of a wall panel, showing my new design; and

FIG. 2 is a perspective view from the rear thereof.

I claim:

The ornamental design for a wall panel, substantially as shown.
